UNITED STATES PATENT OFFICE.

EDWARD W. STEPHENS, OF ERIE, PENNSYLVANIA.

ORE-CONCENTRATOR.

SPECIFICATION forming part of Letters Patent No. 325,129, dated August 25, 1885.

Application filed January 14, 1884. (No model.)

To all whom it may concern:

Be it known that I, EDWARD W. STEPHENS, a citizen of the United States, residing at Erie, in the county of Erie and State of Pennsylvania, have invented certain new and useful Improvements in Ore-Concentrators; and I do hereby declare the following to be a full, clear, and exact description of the invention, such as will enable others skilled in the art to 10 to which it appertains to make and use the same.

This invention relates to that class of ore-concentrators in which the ore-bed is moved; and it consists in certain improvements in means for actuating the ore-bed, as will be 15 hereinafter fully described, and pointed out in the claims.

My device is illustrated in the accompanying drawings, as follows: Figure 1 is a side elevation. Fig. 2 is a top or plan view, with 20 parts broken away to show other parts. Fig. 3 is a vertical section at one end of the machine on the line *x x* in Fig. 4. Fig. 4 is an end elevation with parts broken away.

The machine is rectangular in form, and 25 the one which I have constructed is ten feet long and six feet wide. The stationary framework consists of a base-frame, I, of square timber, and iron upright brackets I' I' at each end. A main shaft, 3, is adjusted in the middle of the frame and extends from end to end. It is run from a driving-shaft and gears 1 1 30 and 2, or it may be run from a belt where mounted directly upon it. At each end of the frame, mounted on the brackets I' I', are upright shafts 6 6, which are run from the shaft 3 by gears 4 and 5. On the top of these upright shafts are crank-heads 7 7, with adjustable crank-pins 8 8, which are adjusted by the screws 9 9. (See Figs. 3 and 4.) The 35

crank-pins pass transversely through trunnion-bars 10 10, which are mounted in boxes H H on cross-beams of a frame, G. This frame is supported on these trunnions and on universally-jointed toggles J J J J at each 45 corner of said frame. These toggles are provided with round ends, which are inserted in cups *j*, attached to the frame G and arc-shaped blocks J'. In Figs. 3 and 4 this arrangement is clearly shown. However, in 50 Fig. 4, the boxes H H are broken away, but are clearly seen in Fig. 3 and also in Fig. 1.

It will be seen that as the shafts 6 6 are revolved the frame G is given a horizontal rotary or orbital movement, the radius of the circle of rotation being adjusted by the adjustment of the crank-pins 8 in the heads 7. It will also be seen that as this rotation takes place the toggles J will lift the frame up first on one side and then on the other, thus rocking it on its trunnions 10. The degree of this rocking is also adjustable by adjusting the feet of the toggles on the arc-shaped blocks J', which are attached to the base I. The throw of these toggles is shown by dotted lines in Figs. 4 and 1. 65

A second frame, F, is mounted on the frame G on rollers L L' in brackets K at the four corners. This frame F is so held that it receives all the movements given to the frame G, and it may also be moved longitudinally 70 on its rollers L L' independently of the frame G. Such a longitudinal movement is given to this frame by the following appliances: On the shaft 3 is an eccentric, 19, which is connected by a connecting-rod, 18, with an arm, 16, said connection being made by a universal joint, 17, said arm 16 being collared upon a shaft, 11, on which is a disk, 13, having a catch, 14, and on the arm 16 is a pawl, 15, which engages with the catch 14. So At the ends of shaft 11 are disks 12 with catch-pins f', which engage with catch-pins f on the sides of the frame F. When the arm 16 is pulled down by the eccentric 19, the shaft 11 is rocked, and this, by reason of the 75 catches f f', draws the frame F forward; but when the arm 16 has been depressed a certain distance the pawl 15 comes in contact with the stop-pin 21, (see Figs. 1 and 3,) and is thrown off the catch 14. 90

The part 20 consists of a bar hinged to the body of stop 21, and extends through the pawl 15. Interposed between the hinge and pawl is a coiled spring, which is compressed when the frame is drawn forward, and forces the 95 pawl into the position shown in Fig. 1 when the latter is released. When this occurs, a reacting spring, F', which is adjusted to resist the separation of the buffers F' G', suddenly drives the frame F back, giving it a sudden 100 jerk. The buffers F' and G' are preferably angle-irons attached, respectively, to frames

F and G. To buffers G' is attached a rod having a set-screw at its distal end, and a coiled spring, F², interposed between the set-screw and the buffer F', so that when the frame 5 F is drawn back the spring will be compressed and will force the buffers together when the pawl has been released from catch 14. This whole movement need not be more than a quarter of an inch.

10 A rubber plate, g, may be put between the buffers F' G' to prevent noise, if desired.

It will now be seen that the frame F has imparted to it a horizontal rotary and a vertical oscillatory and a sudden intermittent longitudinal movement. On this frame I mount the ore-bed, and thus to it is imparted all the forenamed movements, as well as a continuous longitudinal or feeding movement. The manner of so mounting the ore-bed is as follows: At each end of the frame are brackets B², which are provided with an adjustable part, B³, which is mounted on guides B⁴ on the part B². The said parts B³ carry the journal-boxes of the drums B', on which the endless ore-bed B is adjusted. The brackets B², at one end of the frame, are mounted so as to be movable on plates B⁵, and made adjustable by screws B⁶, so as to properly adjust the drums to the length of the belt-like bed B. The screws B⁶ are inserted in screw-threaded lugs b⁶ on plates B⁵, and work in sockets b⁷ in the frame B². If it be desired to adjust the frame B² toward the front of the machine, the screw nearest the front is partly unscrewed, and the screw at the other side of the frame screwed in until the desired adjustment is made. On each side of the upper part of the bed are rails B⁷, in which are journaled rollers b b b, &c., which prevent the bed B from sagging 35 between the drums. The bed may be set perfectly level, but I prefer to give it a slight incline toward the tail. The bed is made to move slowly toward the head—that is, up the incline. This movement is effected by a slow 40 rotation of one of the drums by clutching device 28 and 27, (as shown it is a friction or binding clutch, but it may be a toothed ratchet, if desired,) which is operated by the rod 26, crank 25, rock-shaft 22, rock-arm 24, and eccentric 23. The crank 25 is made adjustable, so as to regulate the degree of movement. A is the feeding-hopper; C, the water supply; D d d, water-jets for clearing the concentrations or headings from the bed. E is 45 the headings-receiver.

The bed B may be made of india-rubber or of metal, and it may be in one piece.

The surface of the bed is divided into a series of pan-like spaces, B⁸, by curved riffles. 50 The bottom of these riffles may be flat, as shown in Fig. 2, or depressed, as shown in Fig. 3. The riffles catch and retain the matter being acted upon, and also serve as dams to the water; and, being curved, the water and sand are held as in 55 a pan, and the rotary motion given to the bed agitates the water and sand substantially the same as a miner agitates them in a hand-

pan. The light particles of sand escape with the water over the top of the riffles and pass toward the tail end of the machine, while the ore is retained in the pans, and is thus carried toward the head of the machine. The bed is made with side pieces or flanges, to prevent the matter being acted or operated upon from escaping at the sides.

70

The jerking or jarring movement is for the purpose of moving pebbles or coarse pieces of rock which are not weighted with ore, and which are too heavy to be washed over the riffles by the action of the water toward the tail end of the machine; and hence, when such matter does not exist in the auriferous matter being operated upon, the said jarring movement is not necessary. From the foregoing description the operation can be sufficiently 85 understood without further description.

75

What I claim as new is—

1. In a wet-ore concentrator, the combination of an ore-bed having a series of curved riffles forming a series of pan-like spaces, a frame supporting said ore-bed, and mechanism for actuating said ore-bed in a horizontal orbit, substantially as described.

80

2. In a wet-ore concentrator, the combination of an endless-belt ore-bed having a series of curved riffles forming a series of pan-like spaces, drums on which said ore-bed is mounted, a frame supporting said ore-bed and drums, and actuating mechanism, substantially as described.

85

3. In a wet-ore concentrator, the combination, substantially as described, of the following elements: an ore-bed having a series of riffles forming a series of pan-like spaces, a frame supporting said ore-bed, gearing, substantially as described, for moving said frame in a horizontal orbit, a base-frame, and universal-jointed toggles for giving said frame a tipping movement as it is rotated, substantially as shown.

90

4. In a wet-ore concentrator, the combination, substantially as described, of the following elements: an ore-bed, frame-work for supporting said ore-bed, consisting of two frames, one of which supports the ore-bed and rests upon the other, and is movable thereon longitudinally, gearing, substantially as described, for moving both said frames in an orbit, and other gearing, substantially as described, for reciprocating the upper frame 115 upon the lower while both are being rotated, as set forth.

95

5. In a wet-ore concentrator, the combination, with the ore-bed B, mounted and moved as a conveyer, substantially as described, of the frames G and F, the upright shafts 6 6, crank-pins 8, toggles J J, trunnions 10 10, and crank-heads 7 7 for supporting and moving said frames, in the manner and for the purposes set forth.

100

6. In a wet-ore concentrator substantially as described, the combination, with the ore-bed B and the frames F and G, of the upright shafts 6 and 6, adjustable cranks 7 8 and 7 8,

105

110

115

120

125

130

the trunnions 10 and 10, and the toggles J J
J J, substantially as and for the purposes men-
tioned.

7. The combination, substantially as herein
described, with the ore-bed B, of the frames F
and G, cranks 7 8, trunnions 10, toggles J, and
the arc-shaped foot-plates J', for the purposes
mentioned.

8. The combination, with the ore-bed B and
the frames F and G, of the buffers F' G', spring
F², the shaft 11, disks 12 12 and 13, catches
f f, f' f', and 14, pawl 15, arm 16, connecting-

rod 18, and eccentric 19, as described, and
for the purposes mentioned.

9. The combination, with the bed B and 15
drum B', of the clutch device 27 28, rod 26,
crank 25, shaft 22, arm 24, and eccentric 23, as
described, and for the purposes mentioned.

In testimony whereof I affix my signature in
presence of two witnesses.

EDWARD W. STEPHENS.
